UNITED STATES PATENT OFFICE.

FREDERICK C. NICKOL, OF DAYTON, OHIO.

FLUSHING APPARATUS FOR WATER-CLOSETS.

No. 901,185.

Specification of Letters Patent.

Patented Oct. 13, 1908.

Application filed April 2, 1898. Serial No. 422,730.

To all whom it may concern:

Be it known that I, FREDERICK C. NICKOL, a citizen of the United States, residing at Dayton, in the county of Montgomery and State of Ohio, have invented certain new and useful Improvements in Flushing Apparatus for Water-Closets; and I do declare the following to be a full, clear, and exact description of the invention, such as will enable others skilled in the art to which it appertains to make and use the same.

My invention relates to flushing apparatus for water closets, and particularly to that type of apparatus which is automatic in action.

The object of the invention is to provide a device of this character which is cheap to construct and positive in its operation and withal of such formation as will occupy comparatively little room and will present a neat appearance.

A further object of the invention is the provision of means which positively regulates the amount of water which is to be fed to the closet at each flushing and at the same time to feed the water thereto under pressure.

A still further object of the invention is the provision of means for automatically placing the water feeding means into operative position upon the use of the closet, and to cut off simultaneously the water thereto until the weight upon the seat is removed, and further to hold the inlet valve open for a predetermined length of time and to automatically release it.

With these and other objects in view, the invention consists of certain novel features of construction, combination and arrangement of parts, as will be more fully described and particularly pointed out in the appended claims.

In the accompanying drawings, Figure 1 is a side elevation showing the relation of the operating mechanism with the closet bowl, Fig. 2 is a vertical longitudinal section, Fig. 3 is a top plan view, Fig. 4 is a horizontal section taken on the line 4—4 of Fig. 2, Fig. 5 is a vertical sectional view taken on the line 5—5 of Fig. 2.

Referring more especially to the drawings, 1 represents the closet bowl, and 2 the seat which is pivoted upon the upstanding lugs 3, as is usual and is provided upon its under side with a valve operating arm 4, to be hereinafter described. The closet bowl in

this instance is provided with a rearwardly extending coupling member 5, to which the closet union 6, is secured by screw threads or other suitable means. The reduced member of the union has attached to it a connecting device 7, provided with a central bridge piece 8, extending across the connection and centrally apertured so as to receive the valve rod 9, of the shut off valve 10. 60 Beyond the bridge piece the connection is somewhat enlarged to receive the threaded and reduced end 11, of the exit valve coupling 12, which is threaded to the valve neck 13, carried by the casing 14, and having its 65 outer part ground to form a valve seat. At the opposite end of the casing a valve neck 15 is provided which is connected by a coupling 16, with the water supply pipe 17. This valve neck 15 leads up into the casing 70 and has forming an integral part thereof the discharge nozzle 18, which will be hereinafter described. Slidably mounted within the casing 14 is the inlet valve rod 19, carrying upon its lower end the valve 20, provided with a rubber gasket adapted to engage the inner side of the valve neck 15 upon which it is normally seated by the action of the spring 21, which surrounds the rod and is limited in its movement by a pin and 75 washer, as is usual. The upper end of the rod passes through the stuffing box 22, in the top 23, and is engaged at its upper end by a lever 24, which is pivoted intermediate its length upon a standard 25, carried by the 80 casing so as to depress the valve rod 19 and valve 20 when actuated by the arm 26, carried by the rear end of the seat and slotted at 27, to engage the pin 28, upon the forward end of the lever 24. The exit valve rod 9 extends through the bridge pieces 29 and 8 and into engagement with the arm 4 of the seat, and a spring 30, which surrounds the shaft 9 and abuts the bridge piece 8 at one end and a washer 31 at the other end, which is held in 85 position by a transverse pin 32, forces the rod outwardly and raises the seat through its action on the arm 4, slightly above the edge of the board upon which it rests when the closet is being used at the same time the 90 valve 10 is held off its seat. This action of course depresses the arm 26 and allows the spring 21 to force the valve 20 into engagement with its seat and close the inlet. When the closet is being used the weight upon the 95 seat causes the arm 4 aforesaid to exert pressure on the rounded end of the valve rod 9,

to close the valve 10 upon its seat in the neck 13. This same action raises the arm 26 and the inner end of the lever 24 thus depressing the rearward end of the lever and consequently the valve rod 19. This action carries the valve 20 off its seat and permits the water to flow through the nozzle 18 into the water canal 33. In order to hold the valve in this position I provide a mechanism which I shall now describe. The top plate 23 is provided with a pair of depending side members or plates 34, in which is journaled a shaft 35, carrying intermediate its length the pawl 36, which is weighted at its outer end to normally force its forward end 36' into engagement with a notch 37, formed in the rod 19. As the valve is depressed by the action of the lever 24 which is controlled by the weight upon the seat, the forward end 20 of the pawl 36 falls into the notch 37 and holds the valve 20 off its seat. This condition of affairs would permit the water from the inlet supply pipe 17 to continue to run after the seat had been vacated and the valve 25 10 carried off its seat by the spring 30. In order to limit the amount of water supply to the nozzle I journal a shaft 38 between the plates 34 and key thereto a water wheel 39, having a plurality of arms extending down 30 into the path of the water in the canal 33. Adjacent the wall I provide a bevel gear 40, which meshes with a similar gear 41, carried upon the short shaft 42, which is journaled in brackets 43. Between these brackets 35 the shaft is provided with screw threads 44, which engage with a worm gear 45, carried upon the transverse shaft 46, also journaled between the plates 34. This worm gear 45 has mounted upon its side a wheel 40 47, which is provided with a cam lug 48, adapted to engage the underside of the pawl 36 so as to release it from the notch 37.

In order that the operation of the device may be better understood it will be stated that when the closet is occupied the arm 4 is necessarily pressed against the valve rod 9, thus closing the valve 10 and at the same time the arm 26 is operated to control the lever and open the valve 20. This prepares 50 the device for the operation of the flush which is started immediately that the seat is vacated. When this is done the seat is raised under the tension of the spring 30, which at the same time releases the valve 10 and the arm 26 is depressed allowing the spring 21 to force the valve 20 to its seat. But owing to the fact that the pawl 36 is in engagement with the notch the valve is held open and the pin 28 slides idly in the slot 27. The 55 water continues to pass through the nozzle 18 and act upon the water wheel to give it a predetermined number of revolutions. Preferably a worm gear is used, constructed so that it will make one complete revolution for every nine revolutions of the water wheel.

As the cam lug 48 reaches the under side of the pawl 36 its rear end is tilted on the shaft 35 and releases it from the notch 37, thus allowing the spring 20 to close the valve 10 upon its seat and cut off the water supply. 70

From the foregoing description, taken in connection with the accompanying drawings, the construction and operation of the invention will be readily understood without requiring a more extended explanation. 75

Various changes in the form, proportion and the minor details of construction may be resorted to without departing from the principle or sacrificing any of the advantages of this invention as defined in the appended 80 claims.

Having thus described my invention what I claim and desire to secure by Letters Patent is:—

1. In a device of the class described, the combination with a closet bowl, of a seat therefor, a suitable source of water supply for flushing said bowl, an inlet valve, an outlet valve, means simultaneously controlled by the seat for closing the outlet valve and opening the inlet valve and for raising the seat to normal, means for holding the inlet valve in an open position, and means controlled by the flow of water for releasing said holding means. 95

2. In a device of the class described, the combination with a closet bowl, of a suitable source of water supply for flushing the same, an inlet valve, an outlet valve, means actuated by the seat for closing said outlet valve, a lever actuated by the seat for opening said inlet valve simultaneously with the closing of the outlet valve, a pawl for holding the inlet valve open, means for opening said outlet valve after the seat has been released, and means controlled by the water flow for releasing said pawl. 100

3. In a device of the class described, the combination with a closet bowl, of a suitable source of water supply for flushing the same, an inlet valve, an outlet valve, a seat pivoted to the bowl, means on said seat for actuating the outlet valve to close the same, an arm carried by the seat, means actuated by said arm for opening the inlet valve, a spring for opening the outlet valve when the seat is released, a pawl for holding the inlet valve in open position, means for releasing said pawl at a predetermined time, and a spring for closing said inlet valve. 110

4. In a device of the class described, the combination with a closet bowl, of a water supply pipe connected thereto, an outlet valve adapted to close said pipe to the bowl, a seat pivoted on the bowl, an arm carried by said seat for closing the outlet valve upon depression of the seat, an inlet valve for controlling the supply pipe, means controlled by the seat for opening said inlet valve simultaneously with the closing of the outlet valve, 125

means for holding said inlet valve open after the seat has been released, and the outlet valve is open so as to allow a free passage of water to the bowl, a water wheel actuated by the flow of water through the supply pipe, and means controlled by said water wheel for actuating said holding means.

5. In a device of the class described, the combination with a closet bowl, of a water supply pipe connected thereto, an outlet valve adapted to close said pipe to the bowl, a seat pivoted on the bowl, an arm carried by said seat for closing the outlet valve upon depression of the seat, an inlet valve for controlling the supply pipe, means controlled by the seat for opening said inlet valve simultaneously with the closing of the outlet valve, means for holding said inlet valve open after the seat has been released, and the outlet valve is open so as to allow a free passage of water to the bowl, a water wheel actuated by the flow of water through the supply pipe to the bowl, and a cam operated by the water wheel for releasing said holding means.

6. In a device of the class described, the combination with a closet bowl, of a water supply pipe connected thereto, an outlet valve adapted to close said pipe to the bowl, a seat pivoted on the bowl, an arm carried by said seat for closing the outlet valve upon depression of the seat, an inlet valve for controlling the supply pipe, means controlled by the seat for opening said inlet valve simultaneously with the closing of the outlet valve,

means for holding said inlet valve open after the seat has been released, and the outlet valve is open so as to allow a free passage of water to the bowl, a water wheel actuated by the flow of water through the supply pipe, a worm gear operated by said water wheel, and a cam carried by said worm gear for releasing said holding means.

7. In a device of the class described, the combination with a closet bowl, of an inlet water supply pipe connected to the bowl, an outlet valve controlling the water from the bowl, a seat for the closet bowl, means carried by the seat for actuating the outlet valve to close the same upon the use of the closet, a spring for returning said valve to normal position and to raise said seat, an inlet valve controlling said supply pipe, means controlled by the seat for actuating said inlet valve to open the same, a gravity pawl for holding said inlet valve in open position, a water wheel arranged to be operated by the flow of water through said inlet pipe, a worm gear, means operated by the water wheel for revolving said worm, a cam carried by said worm gear to release said pawl, and means to return the inlet valve to normal position.

In testimony whereof I have hereunto set my hand in presence of two subscribing witnesses.
